[57] CLAIM

The ornamental design for a linear surgical stapler, as shown and described.

DESCRIPTION

FIG. 1 is a perspective view of a linear surgical stapler showing our new design;

FIG. 2 is a left side elevational view of the design, the right side elevational view being identical thereto;

FIG. 3 is a top plan view of the design;

FIG. 4 is a bottom plan view of the design;

FIG. 5 is a front elevational view of the design; and,

FIG. 6 is a rear elevational view of the design.
